UNITED STATES PATENT OFFICE.

JAMES W. IVORY, OF PHILADELPHIA, PENNSYLVANIA.

TOOTH CERVICAL CLAMP.

1,414,647.

Patented May 2, 1922.

Application filed December 23, 1921. Serial No. 524,367.

To all whom it may concern:

Be it known that I, JAMES W. IVORY, a subject of the King of Great Britain, residing in the city and county of Philadelphia, State of Pennsylvania, have invented 5 a new and useful Tooth Cervical Clamp, of which the following is a specification.

My invention consists of a tooth cervical clamp having jaws which are adapted to be 10 firmly connected with a tooth and so hold the clamp in position thereon, one of the jaws being adapted to hold the gum effectively removed from a cavity in the tooth whereby the cavity is fully exposed for an operation 15 thereon, said jaw being adjustable on the frame by which it is carried, and other details are provided as will be hereinafter fully described.

The invention is satisfactorily illustrated 20 in the accompanying drawing, but the important instrumentalities thereof may be varied, and so it is to be understood that the invention is not limited to the specific details shown and described, as long as 25 they are within the spirit or scope of the claims.

Figure 1 represents a plan view of a tooth cervical clamp embodying my invention.

30 Figure 2 represents a transverse section of a portion on line 2—2 Figure 1.

Figure 3 represents a side elevation thereof.

Figure 4 represents a longitudinal section 35 thereof on line 4—4 Figure 1.

Figure 5 represents a plan view of a modification.

Figure 6 represents a plan view of a portion 40 of a modification.

Figure 7 represents a transverse section on line 7—7 Figure 6.

Figure 8 represents a plan view of a portion 45 of another modification.

Figure 9 represents a transverse section on line 9—9 Figure 8.

Figures 10, 11, 12 and 13 represent perspective views of different forms of jaws that may be employed.

Similar numerals of reference indicate 50 corresponding parts in the figures.

Referring to the drawings.

1 and 2 designate opposite plates of the frame of the clamp, the same extending transversely from the terminals of the bow 55 3 of the frame

In the plate 1 is the recess 3^x in which is adjustable seated the shank 4 of the jaw 5, the latter extending angularly from the inner end of said shank so that its edge 6 is adapted to engage the adjacent portion 60 of the neck of a tooth adjacent to a cavity in the latter. On the outer end of the plate 2 is the limb 7 which depends at an angle thereto and has fitted to it the operating screw 8 which is adapted to engage the 65 jaw 9 whose edge 10 is adapted to engage the contiguous portion of the neck of a tooth opposite to the edge 6 of the jaw 5, the outer end of said jaw 9 having therein an eye or opening 11 which receives the limb 70 7 of the plate 2, thus connecting said jaw 9 with the latter.

It will be seen that when the screw 8 is operated it forces the jaw 9 against the portion of the tooth while the adjusted jaw 75 5 is forced against an opposite side of the tooth and said jaws will firmly clamp the tooth, the jaw 5 then holding the gum removed from the cavity in the tooth so that said cavity is unobstructed for excavating 80 and filling purposes.

It is also evident that as the shank of the jaw 5 is seated in the recess 3 of the plate 1 the jaw may be adjusted on the neck of the tooth relatively to the position of the 85 cavity therein. Various means may be adapted to hold said shank and consequently the jaw in position on the plate 1. In Figures 1, 2, 3, and 4, I employ the screw 12 which is adapted to enter the plate 1 and 90 have its head 13 overlap the shank 4 and tighten against the same. In Figures 6 and 7, I employ the bar 14 which is placed over the shank and tightened thereagainst by the screw 15 which is passed through said bar 95 into the plate 1.

In Figures 8 and 9 I employ the yoke 15^x which is adapted to embrace the adjacent portion of the plate 1 and is tightened against the same by the screw 16 which is 100 passed through the upper and lower members of said yoke and said plate 1. In Figure 5 the shank 4 is longitudinally split or divided as at 18 so as to expand against the sides of the recess 3 and thus hold the shank 105 in position on the plate 1.

In Figures 10, 11, 12 and 13 I show the edges of the jaws 5 of different configurations to be adapted to various contours of the necks of teeth which they engage so as 110

to produce the best effects of engagement of said jaws with said necks so as to expose cavities of decay of larger diameter that may be more extended laterally or of larger 5 surface on the face of the tooth.

I am familiar with clamps where the frame with labial or lingual jaw is integral with the frame which are held with heavy set screws that are in the way of the 10 operator but know of none that slide in a recess made in a frame that takes up no more space than if the shank with the jaw were integral with the frame it moving in a slot or groove dovetailed into the thickness of 15 the metal in the frame.

While the screw 13 will impinge on the shank 4 of the jaw 5 and hold the same from sliding in the recess 3* it is not for that purpose but will serve to hold the shank in 20 the slot when in a packing box or when not in use as I wish this shank to be held very loosely in the recess 3* so that the operator may adjust it very readily where applying the clamp to the tooth simply by the finger 25 movement whether the cavity is deep on the neck of the tooth or very shallow as it will be readily seen that when the jaws are tightened to the neck of the tooth this adjustable jaw will be held by its own tension in the recess in the frame.

I do not claim that this clamp cannot be used for lateral cavities only. It may also be applied to cavities on the lingual neck

or faces of the tooth by slight changes in 35 Figures 6 and 8.

Having thus described my invention what I claim as new and desire to secure by Letters Patent, is:—

1. A tooth cervical clamp consisting of a frame, tooth clamping jaws, one of which is adjustably supported on a member of said frame, the opposite jaw is supported on another member of said frame, and a clamping screw fitted to the last named member and adapted to engage said opposite jaw. 40 45

2. In a tooth cervical clamp, a frame, tooth clamping jaws, one member having therein a recess in which one of said jaws is adjustably seated, means for retaining the latter named jaw in position, another member of said frame having the opposite jaw supported thereon, a clamping screw on the last named member adapted to engage said opposite jaw. 50

3. In a tooth cervical clamp, a frame, one member of which is provided with a depending limb, tooth clamping jaws one of which is sustained on said limb, and the other jaw is adjustably supported on and secured to an opposite member of the frame, and a 55 screw fitted to said limb adapted to engage the adjacent jaw. 60

JAMES W. IVORY.
